CLAIM

U.S. PATENT DOCUMENTS

I claim the ornamental design for a telescoping washing brush for selectively producing ionized water to eliminate water spots without hand drying, as shown and described.

DESCRIPTION

FIG. 1 is a perspective view of a telescoping washing brush for selectively producing ionized water to eliminate water spots without hand drying showing my new design;

FIG. 2 is an end elevational view thereof;

FIG. 3 is an elevational view of the opposing end thereof;

FIG. 4 is a side elevational view thereof;

FIG. 5 is an elevational view of the opposing side thereof;

FIG. 6 is a top plan view thereof; and,

FIG. 7 is a bottom plan view thereof.
